UNITED STATES PATENT OFFICE

CHARLES P. WETMORE, OF MILWAUKEE, WISCONSIN, ASSIGNOR TO A. O. SMITH CORPORATION, OF MILWAUKEE, WISCONSIN, A CORPORATION OF NEW YORK

RECEDING AND COLLAPSING TAP FOR THREADING PIPE COUPLINGS

Application filed March 5, 1925. Serial No. 13,076.

My invention relates to collapsible taps for threading the tapering interior of pipe couplings of large diameter.

It resides in an improved construction of devices whereby the receding radial movements of the thread chasers are controlled by a speed reducing or low speed mechanism of peculiar type, by the use of which such receding movements are effectuated 10 with mathematical precision.

It resides also in the provision of means operating in conjunction with the speed reducing devices to effect a quick collapse of the thread chasers at the completion of 15 the threading operation, so as to clear the chasers from their engagement with the coupling and permit the withdrawal of the tapping head.

It resides also in the provision of sensitive 20 feeler devices for contacting with the end of the pipe coupling during the threading operation, which feeler devices are arranged and connected to control the action of the speed reducing mechanism while the 25 tapping head carrying the thread chasers is advancing into the coupling and threading it.

It resides also in the provision of automatically 30 operating means for quickly withdrawing the sensitive feeler devices at the moment of collapse, so as to avoid injury to the parts in the event that the feeding devices for the tapping head should continue to operate for a moment after the completion of the threading operation.

It resides also in an adjustable timing device by the setting of which the instant of collapse of the chasers can be predetermined with accuracy.

40 It resides also in a novel angular arrangement of the thread chasers in the tapping head, whereby the chasers are stabilized and an improved threading operation is attained and the accumulation of chips is 45 automatically swept out of the flutes in the tapping head, so that interference with the action of the chasers is prevented.

It resides further in certain novel features of construction and combinations of 50 elements as will hereinafter be more speci-

fically set forth, and the novelty of which will be particularly pointed out in the appended claims.

In the drawings accompanying this specification:

Figure 1 is a longitudinal vertical section view through its central plane showing the construction and arrangement of the parts embodied in my invention.

Fig. 2 is a transverse sectional view on the line 2-2, Fig. 1, looking in the direction of the arrows, showing in elevation the face of the plate or flange by means of which the tapping mechanism is supported in position, together with the provision for holding such mechanism against rotation.

Fig. 3 is a horizontal sectional view on the line 3-3, Fig. 1, showing a detail of the construction shown in Fig. 2.

Fig. 4 is a view in elevation, looking from the lathe head, of my improved tapping head, with the cover for the chasers partly broken away.

Fig. 5 is a transverse sectional view on the line 5-5, Fig. 1, looking toward the lathe head, the view showing in the rear some of the parts shown in Fig. 4.

Fig. 6 is a detached view showing in elevation the tubular spindle provided with oppositely disposed helical slots.

Fig. 7 is a view in end elevation of the part shown in Fig. 6, looking from the right of the said figure, and showing the formation of one element of the timing devices.

Fig. 8 is a view in elevation showing the cooperating face of the adjustable member of the timing device.

Fig. 9 is a view in end elevation, looking from the right of Fig. 1, and showing certain details of construction and arrangement.

Fig. 10 shows diagrammatically the co-acting faces of the timing device.

Fig. 11 is a plan view of a portion of the tapping head showing the angular arrangement of the chasers with relation to the center line of the head.

Referring to the details of construction and arrangement shown in the drawings, the numeral 15 designates one end of a pipe

coupling previously bored out to provide a tapered opening of suitable angularity extending inwardly from each end, and properly chucked in a lathe so as to rotate in a fixed plane, and by such means held in position for interior threading.

The numeral 20, indicates a hollow cylinder designed to be entered in an opening or recess in the tail stock or turret of the lathe, which cylinder is formed at one end with a flange 21. By means of the flange, the element 20-21 is secured in fixed position by cap screws or bolts passing through openings 22 in the flange, and threaded into the tail stock or turret. The cylindrical body or barrel 23 of the tapping head is reduced in diameter at its rear end, and is seated in the bore of the cylinder 20, a circumferential or other shoulder 24 on the barrel 23, by engagement with the face of the flange, forming a positive stop which limits the movement of the barrel rearwardly with relation to its mounting. Adjacent the shoulder 24, the barrel is provided upon its surface with opposite longitudinal grooves 25 and 26, forming key seats for locking keys 27 and 28, which latter are guided in radially extending grooves formed in the front face of the flange 21, such keys being retained in position by cap screws 29 and 30, passing through the keys and threaded into the said flange. The inner ends of the keys have a width equal to that of the grooves 25 and 26, so as to fill the same, and when so positioned will serve to hold the barrel 23 against rotation, by resisting the counter-strains imposed upon the thread chasers 31 in the rotation of the pipe coupling 15, during the operation of threading the latter.

The rear end of the barrel 23 is threaded for the reception of a nut 60, which may be formed as a split ring, capable of adjustment to a suitable position upon the said barrel so as to permit a slight radial vibration of the barrel in its bearing, and yet prevent perceptible axial movement in a forward direction. The parts of the split ring may be clamped in position by means of screws 61 and 62, passing through openings in one part and threaded into the other.

The barrel 23 is enlarged at its forward end so as to provide a head 35, in which the chasers 31 in plural number are mounted so as to have movement in slots formed radially therein. A cap 36, attached to the front end of the head 35, retains the chasers in position in the radial slots and confines them against axial movement with respect to the barrel 23. The said barrel is bored out centrally from end to end, the bore being enlarged at the ends of the barrel, for purposes which will be described hereinafter.

A tubular spindle 40, of less length than

the barrel 23, is mounted for both longitudinal and rotary reciprocating movements in the intermediate reduced portion of the bore in the said barrel. At its rear end, the spindle 40 is provided with a circumferential flange 41, one of the purposes of this feature of construction being to effect the confinement of an expansion spring 42 arranged about the spindle in the enlargement of the bore at the rear end of the barrel 23. One end of the spring rests upon a circular step 43 formed at the inner end of the enlarged bore in the barrel, and the other end bears against the opposed face of the flange 41, through an anti-friction bearing 44 interposed between the end of the spring and the flange, to permit free rotation of the spindle 40. Its other purpose will be stated later.

At its other or forward end, the enlarged bore of the barrel 23 receives a cam 45, formed as a cylinder, it having a sliding fit in the said bore and also in a registering recess formed in the cap 36, fixed upon the head 35 of the barrel. The cam 45 is provided with a plurality of undercut radial grooves, the bottoms of which taper or incline, corresponding in number and arrangement with the radial grooves formed in the head 35. The chasers 31, which operate radially in the said grooves, are inclined at their inner or bottom ends to correspond with the inclined grooves in the cam 45, the angle of such inclination being about 12°, for the purpose of permitting a rapid collapsing movement of the chasers to take place when the cam is withdrawn, and at the same time interposing such direct resistance to the inward pressures upon the chasers that the latter are accurately held up to their work and a forced longitudinal retractive movement of the cam under such pressures is avoided.

At its rear end, the cam 45 is provided with a coarsely threaded shank 46, which co-acts with the threaded interior of the adjacent end 46' of the tubular spindle 40. The said spindle is provided with diametrically opposite, parallel-walled, elongated, helical slots 47 and 48, each such slot extending a little more than once around the spindle. The barrel 23 is provided with diametrically opposite, parallel-walled, straight guiding slots 49 and 50 of the same linear extent as the helical slots in the spindle 40. A sleeve 51, mounted for sliding movement along the barrel 23, supports a transversely arranged pin 52 fixed at its ends in opposite openings in the said sleeve. The said pin is passed through all of the slots in the barrel 23 and the spindle 40, so that when the sleeve 51 is moved along the barrel, a movement of rotation is imparted to the spindle 40 in the adaptation of the helical slots in the spindle to the fixed position of the pin 52.

The sleeve 51 supports a spider 53, the latter having a split hub 54, whereby the spider may be clamped in adjusted position upon the said sleeve. A threaded engagement between the split hub and the exterior surface of the sleeve, permits a precise adjustment of the spider in longitudinal relation to the sleeve to be made. This provision for adjustment is important, inasmuch as the said spider carries the "feeler" devices which determine the time of the operation of the means for effecting the collapse and recession of the thread chasers. The spider 53 supports forwardly a ring 55, which is provided with a plurality of feelers 56, the latter being adapted to engage the end of the rotating pipe coupling 15.

The formation 64 upon the outer face of the flange 41 at the rear end of the spindle 40 constitutes a part of the timing mechanism, the said face being transversely notched, as at 65 and 66, such notches being separated by intermediate flush projections 67 and 68. A timing dog 69 in the form of a disc, co-operates with the face 64 of the spindle 40, the face of the timing dog like the face 64 being also transversely notched, as at 70 and 71, such notches being separated by intermediate flush projections 72 and 73. One notch, as 65 in the part 64 and 70 in the part 69, has a greater width than the other, and correspondingly, one projection, as 67 on the part 64 and 72 on the part 69, is wider upon its face than the other. The relative proportions are indicated in the diagrammatic view, Fig. 10. The disk 69 is provided with opposite arcuate slots 72' and 73' through which extend set screws for securing the same to the end of the barrel 23. The arcuate slots permit a radial adjustment of the disk 69 and thereby enables the relative time of collapse of the thread chasers to be regulated.

The chasers 31 may each be of integral construction, or each unit thereof may be in two parts, one of such parts being formed as a thread cutter 31' and supported upon a base 31² which moves in the radial slots in the head 35. In either construction, the inner end of the chaser will be provided with an inclined lateral rib which is engaged in the undercut inclined slot in the cam 45, so that the chaser will be positively moved radially by a longitudinal movement of the cam in either direction, irrespective of the inward pressure exerted upon the chasers by the coupling 15 during the threading operation.

Viewing Fig. 4, it will be seen that the arrangement of the chasers 31 departs from the usual order of parallelism, and that such chasers are disposed at an angle with relation to the axis and the vertical central sectional plane of the tapping head, instead of being parallel therewith or in the said

plane. I find that the threading operation is facilitated and improved by this arrangement, inasmuch as the chasers are stabilized in a larger degree and the usual chattering attendant upon the older parallel arrangement is obviated. This result I find to be due to the fact that the angular arrangement lengthwise of the chasers, as described, permits the engagement of each chaser to be distributed over a wider section or zone of the coupling at its interior circumferential surface, so that a steadyng effect upon the chasers is produced. The width of the section or zone so engaged depends upon the angle at which the radial slots in the tapping head 35 are disposed, and is defined in Fig. 11 by the dotted and projected dimensional side lines of the chasers parallel with the axis of the tapping head. Further, this particular disposition of the chasers has the function of sweeping the intermediate flutes of the tapping head free from the accumulation of chips which in the older arrangement became entangled with the tapping head and retarded the action of the chasers in cutting the threads, and as a consequence thereof, it was often necessary heretofore to remove these chips by hand. In my invention, the tapping head is self-cleaning, and the accumulation of chips is automatically pushed outwardly and away from the chasers in the angular arrangement of the latter, so that the objections formerly existing are eliminated.

The pitch of the threads connecting the spindle 40 and the cam 45, the inclined meeting surfaces of the inner ends of the chasers and the bottoms of the radial slots in the cam, and the pitch of the helical slots in the spindle 40 constituting a speed reducing mechanism possessing a wide range of refinement of action, are all carefully predetermined with relation to the angle and depth of the tapering bore in the coupling 15, so that the receding movement of the chasers as the threading operation proceeds is proportioned with mathematical precision to such tapering bore. The screw-threaded connection between the spindle and the cam constitutes a swivel by means of which the rotary motion of the spindle is converted into a longitudinal motion of the cam.

The timing dog 69 is set, as indicated in Fig. 10, with the flush faces of the projections in a slight over-lapping arrangement, and the direction of the relative movement of the parts during the threading operation is indicated by the arrows shown in connection therewith. By rotary adjustment of the timing dog, the extent of the rotary movement of the spindle 40 to engage the parts and the moment of collapse of the chasers may be accurately provided for.

The parts as shown in Fig. 1 are in the several positions which they occupy at the

commencement of a threading operation. The pipe coupling 15 is properly chucked in the lathe, with the sliding cam 45 advanced, and the chasers 31 projected into their outermost positions. The spring 42 has been compressed, and the faces of the parts 64 and 69 of the locking dog are brought into the same transverse plane by abutting the flush projections, as indicated in Fig. 10. The tail stock or turret of the lathe supporting the tapping head is advanced until the feelers 56 are in engagement with the end of the coupling. It will be understood that the rotation of the coupling and the automatic feed of the tapping head are synchronized, and that, accordingly such rotating and feeding movements are instituted simultaneously. The engagement of the feelers 56 with the end of the coupling 15, in the manner stated, arrests any further movement of sleeve 51 and the pin 52, while the barrel 23 and tapping head 35, together with the spindle 40, are forced to move forwardly in the feeding movement of the tail stock of the lathe. Consequently, as the barrel 23 moves through the sleeve 51, the pin 52 slides in the straight guiding slots 49 and 50 in the barrel in the advancing movement of the latter, and a slow movement 20 of rotation under perfect control at a greatly reduced speed is imparted to the tubular spindle in the passage of the helical slots 47 and 48 therein over the fixed pin 52, the direction of such rotating movement being indicated by the arrow, Fig. 6. In such rotating movement, the threaded interior end 46 of the spindle takes up the thread on the shank 46 of the cam 45, and gradually withdraws the cam to the rear in accordance with a mathematically ascertained rate. At the moment that the receding chasers 31 have penetrated the bore of the coupling to the depth desired, the spindle 40 has completed so much of its revolution as may be necessary, and the flush faces of the projections on the parts 64 and 69 have cleared themselves from each other. The projections on each part will then be in position to engage by passing into the appropriate notches in the other part, and the spring 42, thus released from confinement, will expand to impart a quickened longitudinal movement to the spindle 40, suddenly withdrawing the cam 45, and effecting the instant and complete collapse of the chasers to disengage them from the coupling. The slight accentuated rotation of the spindle which occurs at such time, due to the movement of the inclined walls of the projections and notches of the parts of the timing device over each other in effecting complete engagement, acts to withdraw the feelers 56 from contact with the end of the coupling and prevents a possible smash, in the event 60 that the feed over-runs to a slight extent.

The tail stock or turret of the lathe is then run back to withdraw the tapping head from the coupling, and permit removal of the latter from the lathe.

The parts may be restored to normal with the chasers 31 in advanced position by a forward pull of the ring 55. The forward movement of the ring 55 effects a reverse rotation of the spindle 40, which in turn effects a reverse movement of the cam 45 and the timing elements so that the machine is restored to the initial operative condition. This construction permits the easy disengagement of the parts of the timing devices. The division of the faces 64 and 69 of the timing device permits a balancing of the forces exerted in relatively rotating the said elements to effect their separation and the compression of the spring 42. The purpose in providing the faces with projection of different widths is to obviate engagement of the notches and projections before the spindle 40 has made a proper revolution. With the pin 52 at the extreme left end of the slots in the barrel 23 and spindle 40, as shown in Fig. 1, the co-operating faces of the timer assume the separated positions shown in Fig. 10.

It is preferable to provide the barrel 23 with two opposite straight guiding slots, and the spindle 40 with two helical cam slots, with a pin passing through all of the said slots, for the reason that a balancing of the forces exerted in rotating the spindle is thereby attained.

A spline 75 seated in registering grooves formed in the head 35 and cam 45, serves to align the radial slots formed in the said parts, so that the chasers may be pushed edgewise into the said slots.

Having thus described my invention, what I claim and desire to secure by Letters Patent of the United States, is:

1. In a collapsible tap, a barrel adapted to be supported at one end and having a head on the other end thereof, the said head being provided with a plurality of radially extending slots, thread chasers arranged for movement in the said slots, a movable cam in the said head for supporting the chasers in operative position, a spindle provided with helical slots and mounted for rotation in the said barrel, a connection between the cam and spindle, and a pin passing through the helical slots, whereby upon movement to advance the tap the spindle is rotated to move the cam and permit recession of the chasers.

2. In a collapsible tap, a barrel provided with a plurality of radially extending slots, thread chasers arranged for movement in the said slots, a cam movable in the barrel and supporting the chasers in operative position, a spindle mounted for rotation in the said barrel and provided with helical slots, a

- connection between the cam and spindle, and a pin supported in a stationary position entering the helical slots, whereby upon advancement of the barrel the spindle is rotated to move the cam and permit recession of the chasers.
3. In a collapsible tap, a barrel provided with a plurality of radially extending slots, thread chasers arranged for movement in the said slots, a cam movable in the barrel and supporting the chasers in operative position, a spindle mounted for rotation in the said barrel and provided with helical slots, a screw connection between the cam and spindle, and a pin supported in a stationary position entering the helical slots, whereby upon advancement of the barrel the spindle is rotated to move the cam and permit recession of the chasers.
4. In a collapsible tap, a barrel having straight slots in opposite sides thereof and provided also with a plurality of radially extending slots, thread chasers arranged for movement in the radial slots, a cam movably axially in the barrel and supporting the chasers in operative position, a spindle provided with helical slots and mounted for rotation in the barrel, a screw connection between the cam and spindle, a pin movable in the straight and helical slots, and means for sustaining the pin in stationary position, whereby upon advancing movement of the barrel the spindle rotated to withdraw the cam to permit recession of the chasers.
5. In a collapsible tap, a barrel having a straight slot in the side thereof and provided at one end with a plurality of radially extending slots, thread chasers arranged for movement in the radial slots, a cam sliding longitudinally in the barrel and supporting the chasers in operative position, a spindle provided with a helical slot about the same, a connection between the cam and spindle, and means as a pin sustained in stationary position entering the straight slot of the barrel and the helical slot of the spindle, whereby in the advancing movement of the barrel the spindle is rotated to withdraw the cam and permit recession of the chasers.
6. In a receding and collapsible tap, a barrel having a head provided with a plurality of radially extending slots, thread chasers arranged for movement in the said slots, a cam sliding in the barrel and supporting the chasers in operative position, a spindle mounted for both rotary and longitudinal movements in the barrel, connections between the cam and spindle, means for rotating the spindle to move the cam and permit recession of the chasers, and means for moving the spindle longitudinally to effect collapse of the chasers at the termination of the threading operation.

7. In a receding and collapsible tap, a barrel provided at one end with a plurality of radially extending slots, thread chasers arranged for movement in the said slots, a cam sliding in the barrel and supporting the chasers in operative position, a spindle mounted for both rotary and longitudinal movements in the barrel, connections between the cam and spindle, means for rotating the spindle to withdraw the cam and permit recession of the chasers, means for restraining the spindle from longitudinal movement during such recession, and means for moving the spindle longitudinally to effect collapse of the chasers at the termination of the threading operation.
8. In a receding and collapsible tap, a barrel provided at one end with a plurality of radially extending slots, thread chasers arranged for movement in the said slots, a cam sliding in the barrel and supporting the chasers in operative position, a spindle mounted for both rotary and longitudinal movements in the barrel, connections between the cam and spindle, means for rotating the spindle to withdraw the cam and permit recession of the chasers, means for restraining the longitudinal movement of the spindle during such recession but operative in the rotation of the spindle to release it from such restraint, and means to move the spindle longitudinally to effect collapse of the chasers at the termination of the threading operation.
9. In a receding and collapsible tap, a barrel provided at one end with a plurality of radially extending slots, thread chasers arranged for movement in the said slots, a cam sliding in the barrel and supporting the chasers in operative position, a spindle mounted for both rotary and longitudinal movements in the barrel, connections between the cam and spindle, means for rotating the spindle to withdraw the cam and permit recession of the chasers, an expansion spring for imparting longitudinal movement to the spindle, and means for releasing the spring pressure at the conclusion of the threading operation to effect collapse of the chasers.
10. In a receding and collapsible tap, a barrel provided at one end with a plurality of radially extending slots, thread chasers arranged for movement in the said slots, a cam sliding in the barrel and supporting the chasers in operative position, a spindle mounted for both rotary and longitudinal movements in the barrel, connections between the cam and spindle, means for rotating the spindle to withdraw the cam and permit recession of the chasers, an expansion spring confined about the spindle, and means for releasing the spring pressure at the termination of the threading operation to effect collapse of the chasers.

move the spindle longitudinally and effect collapse of the chasers.

11. In a receding and collapsing tap, a barrel having at one end a head provided with a plurality of radially extending slots, a cam sliding in the said head, thread chasers arranged for movement in the said slots and supported in operative position by the cam, a rotating spindle connected at one end to the cam, means for rotating the spindle to withdraw the cam and permit gradual recession of the chasers, and means for moving the spindle longitudinally to effect collapse of the chasers at the termination of the threading operation.
12. In a receding and collapsing tap, a barrel having at one end a head provided with a plurality of radially extending slots, a cam sliding in the said head, thread chasers arranged for movement in the said slots and supported in operative position by the cam, a rotating spindle connected at one end to the cam for withdrawing the cam to permit the gradual recession of the chasers, means for moving the spindle longitudinally, and means for restraining such movement, such restraining means comprising devices operative in the rotation of the spindle to free the spindle and its connected cam for longitudinal movement to effect collapse of the chasers at the termination of the threading operation.

13. In a receding and collapsible tap, a barrel provided at one end with a plurality of radially extending slots, thread chasers arranged for movement in the said slots, a cam sliding in the barrel and supporting the chasers in operative position, a spindle mounted for both rotary and longitudinal movements in the barrel, connections between the cam and spindle, means for rotating the spindle to withdraw the cam and permit recession of the chasers, a timing device for restraining the longitudinal movement of the spindle, and means for effecting such movement when permitted by the timing device to effect collapse of the chasers at the termination of the threading operation.

14. In a receding and collapsible tap, a barrel provided at one end with a plurality of radially extending slots, thread chasers arranged for movement in the said slots, a cam sliding in the barrel and supporting the chasers in operative position, a spindle mounted for both rotary and longitudinal movements in the barrel, connections between the cam and spindle, means for rotating the spindle to withdraw the cam and permit recession of the chasers, a confined expansion spring for moving the spindle longitudinally, and means for compressing the spring, the last named said means comprising a timing device operating in the rotation of the spindle to release the spring

pressure to move the spindle longitudinally and effect collapse of the chasers at the termination of the threading operation.

15. In a receding and collapsing tap, a barrel having a head provided with a plurality of radially extending slots, a cam sliding in the barrel, thread chasers arranged for movement in the said slots and supported in operative position by the cam, a spindle mounted for both rotary and longitudinal movements in the barrel, means for rotating the spindle to permit a gradual recession of the chasers during the threading operation, and means at the end of the spindle and co-operating means at the end of the barrel for restraining the longitudinal movement of the spindle until the latter has rotated to permit such longitudinal movement to effect collapse of the chasers.

16. In a receding and collapsing tap, a barrel provided at one end with a plurality of radially extending slots, thread chasers arranged for movement in the said slots, a cam sliding in the barrel and a rotating and longitudinally movable spindle connected to the cam, means for rotating the spindle to effect separate movement of the cam to permit recession of the chasers, means for longitudinally moving jointly the spindle and its connected cam, means for restraining such longitudinal movement, and means for releasing the spindle to the action of its longitudinally moving means at the conclusion of the threading operation, such releasing means comprising a timing device at the end of the spindle and a co-operating part at the end of the barrel, whereby the collapse of the chasers is effected in the joint longitudinal movement of the spindle and cam.

17. In a receding and collapsing tap, a barrel provided with a plurality of radially extending slots at one end, a cam sliding in the barrel, thread chasers arranged in the said slots and supported in operative position by the cam, a spindle mounted for both rotative and longitudinal movements in the barrel and connected at one end to the cam, means for restraining the longitudinal movement of the spindle in the barrel, means for converting the rotary motion of the spindle while so restrained into a right line motion of the cam to effect withdrawal of the latter and permit recession of the chasers during the threading operation, and means operative in the rotation of the spindle to release the restraining means and move the spindle longitudinally to effect collapse of the chasers at the conclusion of the threading operation.

18. In a receding and collapsible tap, a barrel having straight slotted sides and provided also at one end with a plurality of radially extending slots, thread chasers arranged for movement in the said radial slots,

- a cam sliding in the barrel, a helically slotted spindle mounted for both rotary and longitudinal movements in the barrel and connected to the cam, a sleeve slidably mounted upon the barrel and supporting a pin extending through the said straight and helical slots, means for restraining the movement of the sleeve and pin, means for imparting longitudinal movement to the spindle, means for restraining longitudinal movement of the spindle whereby the latter is rotated by the pin in the advancing movement of the barrel, and means for releasing the spindle in the rotation of the latter to permit its longitudinal movement to effect collapse of the chasers at the termination of the threading operation. 70
- 10 15 20 25 30 35 40 45 50 55 60 65 70 75 80 85 90 95 100 105 110 115 120 125 130
19. In a collapsible tap, a head provided with a plurality of radially extending slots, thread chasers arranged in the said slots, a cam sliding in the head for supporting the chasers in operative position, a rotating spindle, a threaded connection between the cam and spindle whereby during the rotation of the latter the cam is moved to permit recession of the chasers, feeler contacting means, and connections therefrom for effecting rotation of the spindle. 20. In a receding and collapsing tap, a barrel having its side straight slotted and provided also at one end with a plurality of radially extending slots, a cam sliding in the barrel, thread chasers arranged in the radial slots and supported by the said cam, a helically slotted spindle mounted for rotation in the barrel, a contacting feeler device slidably mounted upon the barrel and sustaining in position a pin engaging the straight and helical slots in the barrel and spindle, whereby in the forward movement of the barrel a movement of rotation is imparted to the spindle to withdraw the cam and permit the gradual recession of the chasers. 21. In a receding and collapsing tap, a barrel having its side straight slotted and provided also at one end with a plurality of radially extending slots, a cam sliding in the barrel, thread chasers arranged in the radial slots and supported by the said cam, a helically slotted spindle mounted for rotation in the barrel, a contacting feeler device slidably mounted upon the barrel and sustaining in position a pin engaging the straight and helical slots in the barrel and spindle, whereby in the forward movement of the barrel a movement of rotation is imparted to the spindle to withdraw the cam and permit the gradual recession of the chasers, and means for moving the spindle longitudinally to effect the collapse of the chasers at the conclusion of the threading operation. 22. In a receding and collapsing tap, a barrel having its side straight slotted and provided also at one end with a plurality of radially extending slots, a cam sliding in the barrel, thread chasers arranged in the radial slots and supported by the said cam, a helically slotted spindle mounted for rotation in the barrel, a contacting feeler device slidably mounted upon the barrel and sustaining in position a pin engaging the straight and helical slots in the barrel and spindle, whereby in the forward movement of the barrel a movement of rotation is imparted to the spindle to withdraw the cam and permit the gradual recession of the chasers, means for moving the spindle longitudinally to effect the collapse of the chasers at the conclusion of the threading operation, and means for moving the spindle longitudinally to effect the collapse of the chasers at the conclusion of the threading operation, and means to retract the feeler device by a reverse rotation of the spindle. 23. In a receding and collapsing tap, a barrel provided at one end with a plurality of radially extending slots, a cam sliding in the said slots and supported in operative position by the said cam, means for withdrawing the cam to permit the gradual recession of the chasers during the threading operation, such means including a rotating and longitudinally movable spindle disposed in the barrel and connected at one end to the cam and provided at the other end with projections and notches, and a timing dog mounted upon the other end of the barrel and provided with co-operating projections and notches, and means for moving the spindle longitudinally when opposing projections and notches engage to impart additional movement to the cam and effect collapse of the chasers at the conclusion of the threading operation. 24. In a receding and collapsing tap, a barrel provided at one end with a plurality of radially extending slots, a cam sliding in the barrel, thread chasers arranged in the said slots and supported in operative position by the said cam, means for withdrawing the cam to permit the gradual recession of the chasers during the threading operation, such means including a rotating and longitudinally movable spindle disposed in the barrel and connected at one end to the cam and provided at the other end with projections and notches, and a timing dog mounted upon the other end of the barrel and provided with co-operating projections and notches, and means for moving the spindle longitudinally when opposing projections and notches engage to impart additional movement to the cam and effect collapse of the chasers at the conclusion of the threading operation, the said projections and notches having inclined walls to cause a slight further rotation of the spindle at the time of engagement, and to balance the forces of rotation in effecting their separation and restoration to normal position. 130

25. In a receding and collapsing tap, a barrel having a tapping head provided with radially movable thread chasers, retractable means in the head for supporting the said chasers in operative position, a rotating spindle operatively connected at one end to said means, means for rotating the spindle to effect withdrawal of the chaser supporting means and permit the gradual recession of the chasers during the threading operation, means sliding on the barrel and connections therefrom to the spindle rotating means for reversing the rotation of the said spindle to restore the chasers to their initial position.

26. In a collapsible tap, a head, a plurality of relatively movable thread chasers arranged in said head, a movable cam for supporting said chasers in operative position and for effecting a radial movement thereof, a rotatable spindle, means responsive to the relative feeding movement of the thread chasers and the article to be threaded for rotating said spindle, and connections between the cam and the spindle, said connections including means for effecting a linear movement of said cam during the rotation of the spindle.

27. In a collapsible tap, a head provided with a plurality of radially extending slots, radially movable thread chasers arranged therein, a sliding cam for supporting said chasers in operative position and for effecting a radial movement thereof, a rotatable spindle, means responsive to the relative feeding movement of the thread chasers and the article to be threaded for rotating said spindle, and connections between the cam and the spindle, said connections including means for effecting a sliding movement of the cam during the rotation of the spindle.

28. In a collapsible tap, a head provided with a plurality of radially extending slots, radially movable thread chasers in said slots, a sliding cam for supporting the chasers in operative position and for effecting a radial movement thereof, a rotatable spindle, means responsive to the relative feeding movement of the thread chasers and the article to be threaded for rotating said spindle, and a screw thread connection between the cam and the spindle whereby rotation of the latter will effect a sliding movement of the cam.

29. In testimony whereof, I have signed my name at Milwaukee, Wisconsin, this 28th day of February, 1925.

C. P. WETMORE.
